Primary Examiner — Michael C Stout*Assistant Examiner* — Fitzgerald L Butac(74) *Attorney, Agent, or Firm* — Alan D. Kamrath; Karin L. Williams; Mayer & Williams PC(57) **CLAIM**

The ornamental design for a rotary cutter, as shown and described.

DESCRIPTION

FIG. 1 is a perspective view of a rotary cutter showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is another perspective view of the claimed design thereof.

The broken lines depict portions of the rotary cutter in which the design is embodied that are not considered part of the claimed design.
